CLAIM

The ornamental design for a handle for saw and T-square combination tool, as shown and described.

DESCRIPTION

FIG. 1 is a perspective view of a handle for saw and T-square combination tool showing my new design, the structure depicted by means of broken lines being for illustrative purposes only and forming no part of the claimed design; FIG. 2 is a side elevational view of FIG. 1;

FIG. 3 is a front elevational view of FIG. 1;

FIG. 4 is a rear elevational view of FIG. 1;

FIG. 5 is a top plan view of FIG. 1; and,

FIG. 6 is a bottom plan view of FIG. 1.

It is noted that as the right side and left side elevational views are mirror images of one another only one is shown.
